UNITED STATES PATENT OFFICE.

JAMES H. HOCKENBERRY, OF WINTERSET, IOWA.

DOOR-FASTENING DEVICE.

1,359,702.

Specification of Letters Patent. Patented Nov. 23, 1920.

Application filed May 11, 1920. Serial No. 380,660.

To all whom it may concern:

Be it known that I, JAMES H. HOCKENBERRY, a citizen of the United States, and a resident of Winterset, in the county of 5 Madison and State of Iowa, have invented a certain new and useful Door-Fastening Device, of which the following is a specification.

The object of my invention is to provide 10 a door fastening device of simple, durable and inexpensive construction, particularly adapted and designed for use on garage doors, barn doors and the like, and so constructed and arranged as to be capable of 15 locking the door in closed position or for holding the door, when in open position, so that the door will not swing.

With these and other objects in view my 20 invention consists in the construction, arrangement and combination of the various parts of the device, whereby the objects contemplated are attained, as hereinafter more fully set forth, pointed out in my 25 claims and illustrated in the accompanying drawings, in which:

Figure 1 shows an inside elevation of a 30 pair of hinged doors equipped with fastening devices embodying my invention, one of the doors being closed, and the other open.

Fig. 2 shows an inside view of a door in 35 open position; taken on the line 2—2 of Fig. 1; and

Fig. 3 shows a sectional view taken on 40 the line 3—3 of Fig. 1.

In the accompanying drawings I have used the reference numeral 10 to indicate generally the frame member forming part of a building above a door opening.

45 Spaced below the frame member 10 is the sill 11. The wall of the building is indicated at 12.

The building wall is provided with a door opening for which there are provided two 45 outwardly opening doors 13. Since the doors and the fastening devices are of similar construction, I shall explain only one of them in detail.

50 Seured to the frame member 10 on the inside of the building and above each door opening, is an upwardly opening U-shaped yoke 14, the closed end of which projects below the frame member 10 and overlaps the lower part of the door when closed. The 55 lower or closed part of the U-shaped yoke

14 has a portion 14^a which projects downwardly a short distance farther than the other part of the closed end of said yoke.

Secured to the inside of the upper portion of the door 13 is an eye-bolt or the like 60 15, which is so arranged that when the door is closed, the eye of the eye-bolt 15 projects substantially through the yoke 14 as illustrated, for instance, in Fig. 3.

I provide what I may call a locking rod 65 16 having at one end a ring 17, received in the eye of the bolt 15. When the door is closed the rod 16 hangs downwardly, as illustrated particularly in Fig. 1. Near its lower end the rod 16 has an inwardly extending portion 18 forming a handle and terminating in a lateral extension 19 adapted to be projected through a keeper 20.

It will be seen that when the parts are in the position last described, a door will be 70 75 locked in its closed position.

It will be noted that the handle portion 18 may be grasped for sliding the extension 19 out of the keeper 20, and thereupon the door may be pushed open. When the door 80 is pushed open, the rod 16 will be raised and will slide through the yoke 14 until the handle member 18, which has generally the shape of a horizontal opening U, engages the yoke whereupon the fore part of the 85 yoke will enter the U-shaped handle member 18 which will then be in downwardly opening position, as illustrated for instance in Fig. 2. This position of the rod 16 will be reached when the door is open, and the 90 door will be held in opened position until the rod 16 is raised to clear the U-shaped handle 18, with relation to the yoke 14.

It will be noted that the parts just described are near the top of the door when 95 the door is open, and I will now describe the device for releasing the rod 16 from its last mentioned position.

Slidably mounted in yokes 21 for vertical reciprocation on the door 13 is an upright 100 rod 22 having at its upper end a portion 23 extending inwardly from the door, as illustrated in Figs. 1 and 3.

Near its lower portion the rod 22 has a portion 24 bent to form a U-shaped handle 105 opening toward the door. At its lower end the rod 22 has a portion 25 bent laterally to extend in both directions from the rod 22 for engaging the door and preventing rotation of the rod 22, and thereby maintain- 110

ing the portion 23 in the right position for the operation about to be described.

The portion 23 stands in such position, when the door is open and the rod 16 is in its upper position, as illustrated in the right-hand part of Fig. 1, and in Fig. 2. The portion 23 stands just below the rod 16. If it is then desired to release the rod 16 from its engagement with the yoke 14 the handle 24 is grasped and the rod 22 is raised slightly causing the member 23 to engage the rod 16 and to raise it sufficiently to cause the yoke 14 to clear the U-shaped handle portion 18. The door may then be readily 15 swung to its closed position.

It will be seen that my device is of very simple and inexpensive construction; that it can be made without expensive machinery or factory equipment; that it can be installed cheaply without the necessity for employing the most skilled labor, and that it has few parts which are likely to get out of order or wear out.

It will also be noted that the door can be 25 thoroughly locked in its closed position with my device, and can be unlocked very easily.

When the door is swung open the parts will automatically assume their position for 30 holding the door in its open position until released therefrom.

Some changes may be made in the construction and arrangement of the parts of my improved fastening device, and it is my 35 intention to cover by my claims any modified forms of structure or use of mechanical equivalents which may be reasonably included within their scope.

I claim as my invention:

40 1. In a device of the class described, a yoke in which a rod may slide, a rod de-

signed to be pivoted to the upper portion of a door, having a U-shaped handle and a lateral extension near its free end, said handle and extension being in different planes, 45 parallel with and intersecting respectively the plane in which the door lies, when the door is closed, a rod designed to be vertically slidably but non-rotatably mounted on the door, having an extension adapted to engage said first rod when the first rod is in substantially horizontal position, for enabling said handle to clear said yoke.

2. In a device of the class described, the combination of a wall having a door opening therein, a hinged upright door for said opening, an inverted U-shaped yoke secured to said wall above said opening and projecting downwardly to position overlapping said door when closed, a member secured to the upper part of said door having an eye, a rod pivoted to said eye, having a U-shaped portion near its free end, and having also a lateral extension near its free end, a keeper on said door for coacting with said lateral 65 extension when the door is closed, a vertically slideable rod mounted on said door for sliding movement, having at its upper end a portion extending inwardly from said door, and at its lower end a portion extending laterally in both directions from said rod for engaging the door and preventing 70 rotation of the rod, a handle on said last rod, said inward extending portion being adapted to stand below said first rod when 75 the door is swung open and said first rod stands in substantially horizontal position with its free end supported by said yoke, and held in position with relation to said yoke by said U-shaped member.

Des Moines, Iowa, April 23, 1920.

JAMES H. HOCKENBERRY.
